FIG. 12.

UNITED STATES PATENT OFFICE.

HARLEIGH GILLETTE, OF HIGHLAND PARK, ILLINOIS.

ELECTRIC GATE.

SPECIFICATION forming part of Letters Patent No. 444,825, dated January 20, 1891.

Application filed October 3, 1890. Serial No. 366,993. (No model.)

To all whom it may concern:

Be it known that I, HARLEIGH GILLETTE, of Highland Park, in the county of Lake and State of Illinois, have invented certain new and useful Improvements in Electric Gates, of which the following is a true specification, reference being had to the accompanying drawings, forming a part thereof.

This invention relates to gates for draw-
10 bridges, railway-crossings, &c., which are worked by electricity; and it consists of improvements in the structural and mechanical parts and electrical devices, whereby a light, strong, and simple structure is produced,
15 readily and quickly operated by electric motors, the circuits of which are controlled from a point or station more or less remote.

Figure 1 is a front elevation of my improved electric gate. Fig. 2 is a section in
20 the plane $v v$, Fig. 1. Fig. 3 is a sectional view of the upper right-hand corner, showing the gate-raising motor and mechanism with the guard-bar raised. Fig. 4 is a sectional view of the opposite or upper left-hand corner, showing the gate-closing motor and mechanism with the guard-bar lowered. Fig. 5 is a cross-section in the plane $x x$, Fig. 4, giving a view of the automatic circuit-breaker from below. Fig. 6 is the side elevation of an engine, showing the position of the devices employed for closing and controlling the circuit of the magnet V, Figs. 11 and 12. Figs. 7 and 8 are side and top views, respectively, of the spring-conducting wheel K, Fig. 6. Fig. 9 is a cross-section of the special rails L L' employed in closing the magnet-circuit. Fig. 10 is an enlarged plan of the circuit-connector O, Fig. 6. Fig. 11 is a plan of the electric circuits for a complete or double railway-
30 crossing gate; and Fig. 12 is an enlarged view of the electro-magnetic motor-circuit switch P, Fig. 11.

In describing my electric gate I will begin with the frame-work. This consists of two
45 hollow iron posts or uprights A A', across the top of which rests a wooden box-beam or cross-piece B, suitably provided, in the usual way, with iron guys or stays b' b² b³ for supporting the same in a rigidly horizontal position. Within the said box-beam and immediately above the upper ends of the two hollow posts are journaled within suitable bear-

ings, affixed to the inner sides of the box-beam, two short shafts, carrying sprocket-wheels S' S², each of which is provided with 55 an ordinary bevel-gear affixed upon the same shaft with the said sprocket and revolving therewith. These bevel-gears C' C² mesh with small companion gears c' c², affixed upon opposite ends of the shaft W, by means of 60 which the two large gears, with their parallel sprockets, are revolved together in opposite directions with uniform speed. Both of the sprocket-wheels S' S² carry sprocket-chains, the outside ends of which are attached 65 to the guard bar or gate proper G and the opposite or inside ends to iron weights suspended within the hollow posts. These weights E and E' are each provided with a hook at the end of a lengthened neck or post e, together with a number of removable independent rings e' e² e³ e⁴, which fit over the said part e, and during the construction of the gate can be removed or replaced at pleasure, in order to exactly counterbalance the guard-bar G. 70

From the above it can be seen that when sufficient power is applied to revolve the shaft W in either direction the guard bar or gate proper G is respectively lowered or raised, as 80 the case may be. The ends of the guard-bar G are provided with semi-annular collars or yokes g g', following the curvature of the posts, as shown in Fig. 2. This construction prevents all longitudinal motion of the guard-bar, provides a guide for steadyng same while being raised or lowered, and, while forming a strongly-braced obstruction when approached from the outside, at the same time permits a team should be accidentally caught between 85 gates. The power I provide by means of two electric motors M and M', one for operating the mechanism to close the gate and the other for reversing the mechanism to reopen the 90 gate. 95

Referring to Figs 3 and 4, I affix upon the shaft W two pulley-wheels D' D². One of these pulleys D' is connected by a belt d direct to the pulley d' upon the armature-shaft 100 of the motor M', and the other D² is connected similarly to the pulley d² on the shaft of the motor M. Thus when the electric current is turned on the motor M the mechanism is op-

erated and the gate closed; but when the said current is switched to the motor M' the mechanism is reversed and the gate opened.

I will now describe the automatic circuit-breaker for the gate-closing motor M . This device consists of a ball J , the conducting-bridge I , and the spring-conductors $i' i'$. Upon these latter the bridge I rests, and thus completes the motor-circuit. In form it consists 10 of a short thick round tube or ring fitting loosely and sliding within the upper part of the post A , which serves as a guide therefor when raised or lowered. The large central aperture freely admits the passage of the 15 chain s , but at the same time is of much less size than the ball J , in consequence of which the said ball catches within and raises the bridge.

The conductors $i' i'$ are provided upon their 20 upper surface with metallic springs (not shown in the drawings) for the purpose of securing better contact with the bridge I when the circuit is closed.

In operation, as the guard-bar G is lowered 25 by the gate-closing motor M , the ball J rises within the gate-post and proceeds until it reaches the bridge I , through which, on account of its size, it is unable to follow the chain, and consequently lifts the said bridge 30 from the conductors $i' i'$, thus breaking the motor-circuit.

Turning to Fig. 3 the automatic circuit-breaker for the circuit of the gate-raising motor M' consists simply of the connecting-lever 35 F , hinged at f^2 to the frame-work and provided with the electrical contact-point f , of platinum or similar metal, and the projection f' , against which the guard-bar G impinges when it has reached the same in rising by the 40 operation of the motor M' . On being lifted by the impinging guard-bar (shown by the dotted lines) the motor-circuit is automatically broken. The electric motors M and M' , with their respective circuits and circuit-breakers, 45 as above specified, are provided, in addition to the necessary electric generator, with an ordinary hand-switch, whereby the current can be switched from one motor to the other. This is preferably made in the form of a rheostat, so that the speed of the motor can be 50 suitably controlled and the full force of the current gradually introduced to prevent the burning of connections. On throwing over the electric switch H , the gate being in the 55 position shown in Fig. 1, motor M is energized and the guard-bar G is lowered to the flanges $a a'$, which position when attained corresponds with that of the mechanism illustrated in Fig. 4. The automatic circuit-breaker 60 there shown is brought into action, (see dotted lines,) the electrical connection is severed and the motor stops. To raise the guard-bar and reopen the gate, the lever of the switch H is thrown back and the electric circuit of 65 the motor M' completed. This motor in operating reverses the gate mechanism. The guard-bar G is lifted until it impinges against

the projection f' , which throws upward the circuit-breaking lever F , breaks the circuit at the point f , and stops the motor. The foregoing constitutes a complete electric gate adapted for all purposes where the circuits are manipulated from a permanent stationary position.

To adapt my electric gate for the protection of railway-crossings and provide means for the automatic working of the gate by passing trains, I employ the electrical devices shown in Figs. 6 to 12. In place of the plain circuit-switch H above mentioned, I substitute the special electro-magnetic switch P , Fig. 11, an enlarged plan of which is shown in Fig. 12. This switch consists of six electrical contact-points $p p' p^2$ and $r r' r^2$, the first and last three of which are respectively connected to the motors M' and M , through graduated resistance-coils from p^2 to p and from r^2 to r in each case, as in an ordinary rheostat. This serves the purpose of more gradually introducing the full force of the current to each 80 motor as the switch-arm is alternately swung back and forth. This switch-arm R is pivoted at its center and provided at one end with the spring-connecting arm r^4 and at the other end with a pin r^3 , working within the 85 slot ℓ^2 upon the end of the magnet armature-lever T . This latter, pivoted at its lower end, is provided upon one side with a strip of soft iron t , forming the armature of the magnet 90 V , and is further provided with a closed tension-spring t' , which draws the armature-lever away from the magnet and holds the same in its normal position. (Shown in the figures.) The electro-magnet V , firmly secured to the frame-work in the position shown, furnishes the means for operating the switch.

In Figs. 6 to 10 inclusive is shown the means for automatically closing the circuit of the magnet V by the approaching and passing engine. This magnet is provided 100 with a generator and one or more circuits depending upon the number of tracks and the direction of passing trains.

In Fig. 11 is shown the plan of circuits adapted for a single track upon which trains 115 pass the crossing in either direction.

In the drawings, $L L'$ are special insulated conducting-rails secured to the cross-ties between the rails of the regular track at positions to the right and left of the center, and are connected together with the regular track-rails $U U'$ within the open electro-magnet circuit, as shown. It being necessary in order to complete the circuit to connect electrically the special rails $L L'$ with the regular track-rails $U U'$, I do this by means of the device shown in Figs. 6 to 10. This consists of a conducting-wheel K , adapted to run upon the special rails $L L'$ and provided with spring-bearings k , attached to the cow-catcher N of the engine at n . (See Figs. 6, 7, and 8.) An ordinary circuit-connector O , placed within the cab for manipulation by the engineer, is also provided for reasons hereinafter stated.

Referring to Fig. 11, an engine approaching from the right as soon as it reaches the section provided with the rail L', which may be extended an eighth or a quarter of a mile 5 up the track, will complete the magnet-circuit from the said rail L' through the wheel K, spring k, circuit-conneeter O, and the driving-wheel of the locomotive X to the rails U U'. The magnet-circuit being closed, the 10 magnet V draws to itself the armature t, attached to the lever T, which latter throws over the switch-arm R, completing the circuit, which operates the motors M M. These motors immediately revolve and lower the 15 guard-arms of their respective gates. When the locomotive reaches the point P, the conducting-wheel K leaves its rail L' and the magnet-circuit is reopened, the switch-lever is drawn back by the spring t' to the position 20 shown in the drawings, and the circuits of the motors M' M' are completed to raise the guards. A train in approaching from the left will complete the magnet-circuit between the rail L and the track U U' and similarly operates 25 the gates, as aforesaid.

While ordinarily the passing engine operates the gates automatically, a circuit-connecting lever O is placed in the cab to enable the engineer to open the magnet-circuit in 30 case the train should stop before reaching the gate, and it thus becomes unnecessary to lower the guards. Upon each of the gates an electric bell b is affixed in a prominent position and provided with a generator and circuits, 35 whereby ample warning is given before the guards are lowered.

In constructing my electric gate I do not confine myself strictly to the mechanical details specified. Well-known equivalents may 40 be substituted in the different parts when found desirable.

Having thus described the several features, I claim as my invention—

1. In an electric gate, the combination, with 45 the posts provided with a guard-bar mechanically connected to two electric motors, a generator, circuits, and circuit-closers therefor,

and two automatic circuit-breakers for same, one of which consists of a hinged connecting-lever provided with a projection adapted to 50 be impinged upon and lifted by the said guard-bar upon reaching its extreme limit of motion, substantially as specified.

2. In an electric gate, the combination, with the posts provided with a guard-bar mechanically connected to two electric motors, a generator, circuits, and circuit-closers therefor, and two automatic circuit-breakers for same, one of which consists of a connecting-bridge 55 mechanically connected to the motor, and provided with a guiding-slide, through which the same is automatically lifted to break the circuit, substantially as specified.

3. In an electric gate, the combination, with the gate proper, mechanically connected to 60 two electric motors, provided with a generator, circuits, and automatic circuit-breakers, of circuit-closers therefor, consisting of a movable switching-conductor provided with a spring and carrying the armature of an electro-magnet, together with the said electro-magnet having its individual circuit, generator, and circuit-closer, substantially as specified.

4. The combination, with the posts and with 65 gate-operating mechanism which includes 70 pulleys, of a guard-bar suspended therefrom and provided with the semi-annular post-yokes g and g', substantially as specified.

5. In an electric gate, the combination, with 75 the gate-posts and cross-beam provided with 80 a guard-bar suspended from pulleys and counterbalanced by weights, of an electric motor for lowering the said guard-bar, mechanically connected to the same, and provided with an electric generator, circuit, circuit-closer, and 85 automatic cut-off, and another electric motor for opening the gate, with a generator, circuit, circuit-closer, and automatic cut-off therefor, substantially as specified.

HARLEIGH GILLETTE.
